UNITED STATES PATENT OFFICE.

JOHN B. GRAVIS, OF CANTON, OHIO.

DESIGN FOR A METALLIC PLATE FOR ELASTIC-TREAD HORSESHOES.

SPECIFICATION forming part of Design No. 33,791, dated December 25, 1900.

Application filed October 27, 1900. Serial No. 34,671. Term of patent 14 years.

To all whom it may concern:

Be it known that I, JOHN B. GRAVIS, a citizen of the United States, residing at Canton, in the county of Stark and State of Ohio, have invented and produced a certain new and original Design for a Metallic Plate for Elastic-Tread Horseshoes, of which the following is a specification.

My invention relates to a new and useful design of a metallic plate for elastic-tread horseshoes; and it consists of a metallic plate of the configuration and ornamentation shown in the accompanying drawing, which is a perspective view thereof.

The leading feature of my design consists of a horseshoe-shaped plate A, having formed on the outer edges thereof clips a, which extend around the outer edge of the plate and terminate just forward of the inner edges of the heels, inwardly-projecting horizontal

flanges b and c formed upon said clips at the heels and a corresponding inwardly-projecting flange d at the toe, and a short vertical flange e formed upon the inner edge of the plate opposite the toe.

These plates are sold to the trade and are used in conjunction with rubber cushions intended to be inserted therein and engaged therewith by means of the clips and horizontal flanges.

What I claim is—

The design for a metallic plate for elastic-tread horseshoes, herein shown and described.

In testimony whereof I have hereunto set my hand in the presence of two subscribing witnesses.

JOHN B. GRAVIS.
